UNITED STATES PATENT OFFICE.

FRANK J. GILROY, OF BUFFALO, NEW YORK.

CAR-DOOR.

1,183,865.

Specification of Letters Patent. Patented May 23, 1916.

Application filed August 19, 1912. Serial No. 715,857.

To all whom it may concern:

Be it known that I, FRANK J. GILROY, a citizen of the United States, residing at Buffalo, in the county of Erie and State of New York, have invented certain new and useful Improvements in Car-Doors, of which the following is a specification, reference being had therein to the accompanying drawing.

10 My invention relates to doors for cars, such as freight, baggage, and express cars, and its general object is to provide a door that shall leave available the full space between doors on opposite sides of the car, that shall be unusually secure against unauthorized opening, that shall fully exclude rain or the like, and that shall be proof against the escape of granular material loaded in bulk in direct contact with the doors.

20 The desired ends are reached by providing the lower and lateral margins of the door with continuous metal flanges which engage corresponding continuous metal flanges fixed to the car around the door opening, and by providing the upper margin of the door with a continuous oblique flange which is overlapped by a similar continuous oblique flange fixed to the car above the door opening. The door is further provided in 25 its upper half with an opening closed by sliding shutters analogous to the door itself, and all parts are secured by devices which cannot be released or removed by unauthorized persons without the car. Still further, 30 the engaging flanges are such that pressure within tends to hold closed all crevices at the joints.

In the accompanying drawings, Figure 1 shows in elevation the middle portion of a 40 freight car provided with a metal bound wood door. Fig. 2 is a like view showing a similar door of metal. Fig. 3 shows the inner face of the door of Fig. 1. Fig. 4 is a section on the line 4—4, Fig. 1. Fig. 5 is a section on the line 5—5, Fig. 1. Fig. 6 is a section on the line 6—6, Fig. 1. Fig. 7 is a section on the line 7—7, Fig. 1. Fig. 8 is a section on the line 8—8, Fig. 2. Fig. 9 is a section on the line 9—9, Fig. 2.

50 The door of Fig. 2 is preferred for new work, but the devices of Fig. 1 are used to apply the invention with slight expense, to ordinary cars and their doors.

55 In the last mentioned construction, shown in Figs. 1 and 3 to 7, A represents the body of a car and B of its wood doors supported

by hangers B' running in a tubular way C fixed to the car above the door and without novelty herein claimed.

The body of this door is made in the usual way but its four sides are provided with continuous metal flange members B², B³, B⁴, B⁵ preferably so made as to receive the margin in a groove and secured to the wood by rivets B⁶ passing through the whole. The lower and right-hand side members B², B³ are bent inwardly and back upon themselves so that they are hook-like in cross-section. The hooked member B² at all times and the member B³ when the door is closed engage, respectively, metal strips D, D' fixed to the car and both concealed and protected when the door is closed. Preferably these members B², B³ and D, D' have no joint at the corners but are bent at the corner point, any joints needed being made in the straight part at some distance from the angle. The left hand member B⁴ at the closing margin of the door is not provided with a hook but has a beveled edge and when the door is closed fits under and against a continuous, vertical member D² fixed to the car and extending from top to bottom of the door. The member B⁴ may be provided on its inner face with a series of wedge-like projections B⁷ adapted to impinge upon the inner face of the groove-like channel into which it enters as the door is closed and thus force the door slightly outward against the member D². The door is further provided with small horizontal T bars or angle irons B⁸ riveted to its external face, and with a pivoted hook B⁹ at its right hand side to be used in applying opening force. The door is locked by concealed devices not here important and not shown, and the car is provided with any suitable stops to limit the door's opening movement. The member B⁵ at the upper edge of the door is provided with an upwardly and inwardly extending flange B¹⁰ which slides longitudinally with the door, beneath a like inclined strip B¹¹ fixed to the car.

Just below the hangers, the door is cut away to form a window, or loading opening, which is closed by (as shown in this instance) two sheet metal shutters E, E' meeting and overlapping at the middle of the opening. Each shutter has its upper, lower and outer marginal portion bent to form a hook E², which engages a corresponding strip E³ fixed to the door and con-

sealed when the shutters are closed. The shutters are secured in closed position by devices on the inside, usually a spring latch E⁴ and catch E⁵.

- 5 In case it is desired, the shutters may be left open at any time to admit light whether or not interior glass windows are used, and at other times they may be closed and locked. It is also obvious that a single shutter may 10 be used, or that but one may be opened when two are employed.

From the construction it follows that when granular bulk material presses against the doors the lower and lateral marginal 15 members of the door are thereby pressed outward firmly against the corresponding members fixed to the car and that no variation in pressure can open any passage for the escape of material. In actual use it has 20 been shown that no amount of rough handling of a grain loaded car, as in switching in making up trains, and in long trips causes any loss whatever. Nor will rain nor even water from a hose cause any material 25 entrance of water. No parts of the device affecting the closure of the door can be removed by the use of a wrench or other tool. It is also clear that there is a gain in interior space, equal to the thickness of the car 30 walls, at the door openings, which is a material advantage with baggage and express cars.

The metal door construction shown in Figs. 2, 8, 9 is analogous. The body M of 35 the door is made of sheet metal having riveted to its edges similar marginal members N, N', N², N³, and to its face horizontal T bars O, all the angles, preferably, being provided with triangular stiffening webs O' 40 integral with or riveted to the marginal members. In this case the shutters P, P' are made as before, but preferably their hooked edges engage outwardly turned and hooked marginal portions Q of the plate or body 45 M. The T bars prevent bulging of the doors and with the angle webs serve as braces. In the ordinary car door construction, the "shoes" are readily removed by any one possessed of a wrench and a pinch bar, and the

lower corner of the door being pried outward and held access to the car is obtained without even breaking the seal. Nothing of the kind is possible with either form of my invention.

What I claim is:

1. The combination with the usual car door of wood, of U-shaped channel members of metal closely embracing the four marginal portions of the door, respectively, and provided with integral flanges adapted to 60 engage suitable flanges fixed to the exterior of the car above, below, and at the rear side of the doorway.

2. The combination with a car, of an outwardly projecting external flange alongside 65 the forward lateral margin of the door opening, to receive the door, and a sliding door adapted to cover said opening and provided upon the inner face of its forward lateral marginal portion with spaced wedge-like 70 ribs for forcing said door outward against said flange as the door approaches the limit of its closing movement.

3. The combination with a car having the usual doorway, of a downwardly and outwardly inclined flange member bolted to the exterior face of the car wall above the doorway, a downwardly projecting flange member fixed to said face below the doorway, rearwardly turned flange members fixed to 80 said face along the forward and rear sides respectively, of the doorway, a wood door mounted to slide along said face and provided at each margin with a closely fitting channel iron binding, the upper channel 85 iron being provided with an upwardly and inwardly inclined integral flange adapted to fit closely under the corresponding wall flange, and the lower and rear channel irons being provided with hook-like integral 90 flanges adapted to engage the corresponding flange members on the car wall.

In testimony whereof I affix my signature in presence of two witnesses.

FRANK J. GILROY.
